A. PAPINI.
ELECTRICALLY OPERATED FLUID HEATER.
APPLICATION FILED AUG. 11, 1919.

1,338,997.

Patented May 4, 1920.

UNITED STATES PATENT OFFICE.

ANTONIO PAPINI, OF PHILADELPHIA, PENNSYLVANIA, ASSIGNOR TO A. MECKY COMPANY, OF PHILADELPHIA, PENNSYLVANIA, A CORPORATION OF PENNSYLVANIA.

ELECTRICALLY-OPERATED FLUID-HEATER.

1,338,997.

Specification of Letters Patent.

Patented May 4, 1920.

Application filed August 11, 1919. Serial No. 316,553.

To all whom it may concern:

Be it known that I, ANTONIO PAPINI, a subject of the King of Italy, and having resided in the United States one year last past and having declared my intention of becoming a citizen thereof, residing in the city and county of Philadelphia, State of Pennsylvania, have invented a new and useful Electrically-Operated Fluid-Heater, of which the following is a specification.

My invention relates to a device for electrically heating water or other fluid, and consists of a heating member in a fluid receiver, and an outlet valve for the latter adapted to be operated by the inflow of the fluid into said receiver, and electric means whereby an electric circuit is formed, and the heating member is energized thus heating the fluid.

The invention is satisfactorily illustrated in the accompanying drawing, but the important instrumentalities thereof may be varied, and so it is to be understood that the invention is not limited to the specific details shown and described, as long as they are within the spirit or scope of the claims.

Figure 1 represents a vertical section of an electrically operated fluid heater embodying my invention.

Fig. 2 represents a top plan thereof.

Fig. 3 represents a horizontal section on the line 3—3 of Fig. 1.

Similar numerals of reference indicate corresponding parts in the figures.

Referring to the drawings.

1 designates a fluid receiving chamber, and 2 designates the cap or cover thereof. 3 designates a divisional diaphragm between the top of the chamber 1 and the bottom of the cap 2, its peripheral portion being seated on the shoulder 4 of the chamber 1, packing 5 being imposed to form tight joints for said chamber, cap and diaphragm.

In the diaphragm 3 is the seat 6 for the valve 7 whose stem 8 is engaged by the spring 9, and fitted slidingly to the pin 10, in the cap 2, said pin being adapted to form a guide for said stem, it being connected with the top of the cap 2 by the nut 11.

12 designates a lever which is pivotally mounted on an ear in the cap 2, passed freely through the valve stem 8 and connected by the piece 13 of insulating material with the bracket or elbow 14, whereby the latter

is adapted to be raised and lowered by said lever.

Connected with the diaphragm below the bracket 14 is the electrode 15 connected with which is the bracket or elbow 16, both brackets being within the cap 2, and having therein opposite limbs provided respectively with the electrodes or contacts 17, which are adapted to make and break an electric circuit by the movement of the bracket 14, as will be hereinafter described.

18 designates an electric wire or conductor which is connected with the bracket 14, and with the electrode 19 on cap 2, said electrode having also connected with it the electric conductor 20.

Within the receiver 1 is the heating element 21 which is composed of a piece of wire bent in zig-zag, spiral, coil or other form, one end of the same being connected with the electrode 15 by the binding screw 22, and its other end being connected with the conductor 25, as hereinafter described, said element thus being in an electric circuit with said conductors 20 and 25.

The chamber 1 is provided with the inlet neck 23 which is adapted to be connected with a source of supply of fluid for directing the latter into the chamber.

The cap 2 has connected with it the nozzle or spout 24 for the discharge of the fluid from the same.

The operation is as follows:—

The fluid is turned on from its source whereby it enters the chamber 1 and fills the same. The inflow of the fluid and consequent upward pressure of the same lifts the valve 7 from its seat and so opens it. The valve stem 8 raises the lever 12 whereby the bracket 14 is also raised and its contact 17 is engaged with the contact on the bracket 16, and so there is a circuit formed by the conductor 18, the electrode 19 and the conductor 20 with the electrode 15, and consequently with the element 21 and from the latter to the terminal conductor 25, through the insulated bushing 26 in the diaphragm 3, and through the insulated bushing 27 in the top of the cap 2, the latter named bushing being secured in position by the binding screw 28, and a suitable nut thereon.

Consequently the element is energized and so the fluid is heated in which condition the fluid enters the cap 2 and discharges there-

from through the nozzle 24. When the fluid is cut off, and the chamber 1 is no longer supplied with the same, the valve 7 is relieved of its upward pressure whereby it closes on its seat. The lever 12 then lowers and with it the bracket 14 whereby the contacts 17 are separated and the electric current is broken whereby the element 21 is no longer energized. The element 21 in its arrangement in the casing, which latter is constructed of metal avoids the formation of an induction in said casing when operated by an alternating current.

By locating the member 3 and the valve and the parts supported by said member at the end of the fluid-receiving chamber farthest remote from the fluid-inlet, the fluid must fill the said chamber before the current is turned on, and, hence, all liability of damage is thus obviated.

Having thus described my invention what I claim as new and desire to secure by Letters Patent, is:—

1. In a fluid heater, a fluid receiving chamber, a valve therein at the end remote from the entrance of the fluid and which is adapted to be opened by the inflow of the fluid into said chamber, a heating element in said chamber, and means connected with said valve for forming an electric circuit and energizing said element.

2. In a fluid heater, contacts, movable and stationary carriers for said contacts respectively, a valve, a lever freely connected with the stem of said valve for operating the movable carrier, means for energizing said contacts, a fluid receiving chamber, a heating element therein, a valve in said chamber at the end farthest remote from the en-

trance of the fluid and adapted to be opened by the inflow of fluid and operate said lever, and an electric circuit for said heating element.

3. In a fluid heater, a fluid receiving chamber, a valve therein at the end remote from the entrance of the fluid and which is adapted to be opened by the inflow of the fluid into said chamber, a diaphragm in said chamber, a lever mounted on said diaphragm and connected with the stem of said valve, an electric contact adapted to be carried by said lever and movable therewith, an opposite contact carried by said diaphragm, electrodes connected with said contacts, a heating element in said chamber, the same being connected with the adjacent electrode, and an electrical conductor connected with the other electrode, and an electrical connection between the movable contact and the last named electrode.

4. In a fluid heater, a fluid receiving chamber having a fluid-inlet at one end, a cap therefor at the other end, a diaphragm between said cap and the adjacent end of the chamber and having opening with valve seat, a contact supported from said diaphragm, a spring-pressed valve, a pivoted lever movable through the valve stem, a contact carried thereby, a heating element in said chamber connected with one of said contacts, and a wire within said cap connecting the other contact with an electrode on said cap.

ANTONIO PAPINI.
